Fritz Zug Jr.
ATTORNEY

UNITED STATES PATENT OFFICE.

JAMES G. BALDWIN, OF NEW YORK, N. Y.

DESIGN FOR A DECORATIVE LIGHTING DEVICE.

Application filed June 5, 1926. Serial No. 17,953. Term of patent 7 years.

To all whom it may concern:

Be it known that I, JAMES G. BALDWIN, a citizen of the United States, residing at 125 20th Street, Jackson Heights, borough and county of Queens, city and State of New York, have invented a new, original, and ornamental Design for a Decorative Lighting Device, of which the following is a specification, reference being had to the accompanying drawing forming a part hereof.

Fig. 1 is a front view and Fig. 2 is a side view of my new decorative lighting device.

I claim:

The ornamental design for a decorative lighting device as shown in the accompanying drawing.

JAMES G. BALDWIN.
